UNITED STATES PATENT OFFICE.

JAMES C. DEMAREST, OF NEW YORK, N. Y., ASSIGNOR TO J. C. DEMAREST & CO., INC., OF NEW YORK, N. Y., A CORPORATION OF NEW YORK.

DESIGN FOR A TABLE.

51,836.

Specification for Design.

Patented Mar. 5, 1918.

Application filed January 21, 1918. Serial No. 213,074. Term of patent 3½ years.

To all whom it may concern:

Be it known that I, JAMES C. DEMAREST, a citizen of the United States, residing at borough of Manhattan, city, county, and State of New York, have invented a new, original, and ornamental Design for Tables, of which the following is a specification, reference being had to the accompanying drawing, forming part thereof.

The figure is a perspective view of a table, showing my new design.

I claim:

The ornamental design for a table, as shown.

JAMES C. DEMAREST.

Witnesses:

K. G. LEARD,
I. M. BARDER.
